UNITED STATES PATENT OFFICE.

GEORGE L. WOOD, OF DENVER, COLORADO.

RAILROAD-TIE.

1,283,011.

Specification of Letters Patent. Patented Oct. 29, 1918.

Application filed September 25, 1917. Serial No. 193,063.

To all whom it may concern:

Be it known that I, GEORGE L. WOOD, a citizen of the United States, and a resident of the city and county of Denver and State 5 of Colorado, have invented certain new and useful Improvements in Railroad-Ties, of which the following is a full, clear, and exact description, such as will enable others skilled in the art to which the invention ap- 10 pertains to make and use the same.

My invention relates to improvements in railroad ties, and the invention has for its object the provision of a metal tie which embodies the cushioning effect of the commonly 15 used wooden tie.

A further object of the invention is to provide a metal railroad tie by means of which the rails may be securely locked thereto without the use of rail spikes.

With these and other objects in view, the invention will be described in detail with reference to the accompanying drawing.

In this drawing, Figure 1 is a plan view of the railroad tie; Fig. 2 is a side elevation 25 view thereof; Fig. 3 is a detail view of one end of the tie, showing the locking lip thereof; and Fig. 4 is a cross sectional view taken on the line 4—4 of Fig. 2.

Corresponding and like parts are referred 30 to in the following description and indicated in all the views of the accompanying drawing by the same reference characters.

Let the numeral 5 designate the central portion of the metal railroad tie, and the numerals 6 and 7 the opposite detachable extremities thereof. The central portion 5, as well as the opposite extremities 6 and 7, are 35 of A-shape, the interior space thereof adapted to be tamped with the dirt, or material of 40 the railroad bed. The tie being of A-shape, the same will yield under the weight of a passing train, and thereby accomplish that degree of cushioning effect incident to a wooden tie. The opposite extremities of the 45 central portion 5 of the tie receive the detachable extremities 6 and 7, and when these 50 detachable extremities are applied, the length of the tie is complete. The extremities of the central portion 5 of the tie are provided with recesses 9 therein which form lips 10,

and the inner extremities of the detachable portions 6 and 7 are provided with similar recesses 12, forming lips 13. The rails 14 rest upon the top of the ties and the bases thereof are received in the opposing recesses 55 9 and 12, the lips 10 and 13 being received over the top of the bases of the rails. These recesses 9 and 12 are of V-shape, whereby the bases of the rails are wedged therein when the detachable portions 6 and 7 are applied and connected with the central portion 5. Ears 15 are cut out of the central portion 5 of the tie and bent at right angles to the body of the latter, and the inner extremities 60 of the detachable portions 6 and 7 are provided with similar opposing ears 16. These ears 15 and 16 are connected together by means of bolts 17, and by tightening the nuts 18, the detachable portions 6 and 7 will be drawn inwardly, causing the bases of the 70 rails 14 to be tightly wedged in the recesses 9 and 12 by reason of the lips 10 and 13. The central portion 5 is provided with cut out lips 19, which extend on the interior of the tie and engage in the bed of the track for 75 the purpose of preventing the tie from moving longitudinally under the influence of centrifugal force of a moving train, or from pressure exerted on said ties in a longitudinal direction.

While I have described and illustrated herein a specific form of the invention, it is understood that I am not limited thereto and that the same may be modified and varied without departing from the spirit of the 85 invention, or the scope of the appended claims.

Having thus described my invention, what I claim and desire to secure by Letters Patent is:—

1. An A-shaped metal railroad tie, comprising a central portion, and detachable end portions received by the central portion and adapted to be secured to the latter, the opposite extremities of the central portion and the inner extremities of the end portions having opposing V-shaped recesses therein adapted to receive the bases of the railroad rails.

2. A metal railroad tie, said tie being of 100

A-shape and comprising a central portion, and detachable end portions received by the opposite extremities of the central portion, the opposite extremities of the central portion and the inner extremities of the end portions having opposing recesses adapted to

receive the bases of the railroad rails, and the tie having inwardly extended portions adapted to engage in the bed of the railroad.

In testimony whereof, I affix my signature.

GEORGE L. WOOD.

Copies of this patent may be obtained for five cents each, by addressing the "Commissioner of Patents, Washington, D. C."
